UNITED STATES PATENT OFFICE

2,197,645

ADJUSTABLE CASKET STOP

Peter O. Krogh, Lima, Ohio, assignor to Superior Body Company, Lima, Ohio, a corporation of Ohio

Application August 17, 1939, Serial No. 290,617

1 Claim. (Cl. 296—18)

This invention relates to hearses, and primarily to stop means therein for engaging the casket to firmly hold it in carrying position.

The object of the invention is the provision, in a hearse, of simple, novel and efficient means attached to the hearse floor and operable and adjustable thereon to suit the size or position of a casket in the hearse and to serve as a stop therefor to hold it in carrying position.

10 Another object of the invention is the provision of an adjustable stop of this character which may be used in any and all types of hearses, such as standard end loading, standard side loading and those having casket supporting tables 15 mounted for guided movements therein.

The invention is fully described in the following specification, and one embodiment thereof illustrated in the accompanying drawing, in which—

20 Figure 1 is a horizontal sectional view of a hearse looking down on the floor thereof, with a casket or casket carrying table in carrying position therein and engaged by a stop means embodying the invention; Fig. 2 is an enlarged fragmentary portion of Fig. 1 including the adjustable stop; Fig. 3 is an enlarged side elevation of the adjustable stop in casket clamping position; Fig. 4 is a similar view, with the stop in vertical section, and Fig. 5 is a vertical cross-sectional view of the stop on the line 5—5 in Fig. 4, with parts in full.

25 Referring to the drawing, 1 designates the floor of a hearse of the side delivery type, 2 either a casket or a casket supporting table disposed in the hearse, and 3 the adjustable stop means embodying the invention.

In jobs where the casket is loaded from the rear, the adjustable stop means will be placed at the rear of the casket, and where the casket 40 is loaded from either side, such means is placed in front of the casket. The two sides and opposite ends of the casket, or of the casket carrying table if one is used, may be held stationary in any suitable manner, as by the conventional 45 bier pins 4 inserted in registering holes in bier pin plates 5, as well understood in the art.

The adjustable stop means in its illustrated embodiment includes a channel guide bar 10 mounted on or set into the hearse floor with its 50 open side up and its upper side edges inwardly flanged, as at 11, to provide a restricted guide slot 12 with undercut side walls. This bar is disposed lengthwise of the hearse and is of sufficient length to start a distance beyond the hearse 55 end to extend a distance thereunder, and is of

suitable length to accommodate all sizes of caskets.

The stop member of the device comprises a hollow block 15 slidably mounted and guided by the bar 10. This block in its present embodiment 5 includes a hollow body part 16 of suitable rigid material, such as metal, plastic or the like, having its bottom and inner side right-angularly disposed and preferably faced with rubber pads 17 and 18, respectively.

10 An eccentric shaft 20 is mounted crosswise in the upper part of the member 16 and journaled on this within the member is a U-shaped clamping yoke 21 having a stem 22 projecting down therefrom through the bottom pad 17 and a guide 15 plate 23 secured at the inner side thereof to the member. The lower end of the stem 22 projects down through the guide bar slot 12 and has a nut threaded thereto within the guide bar and adapted to have clamping engagement with the 20 bar flanges 11 when the eccentric 20 is turned to clamping position, as shown in Figs. 4 and 5. The stem 22 and its nut may be assembled with the guide bar through an open end of the latter.

15 The eccentric 20 has a control handle 25 fixedly 25 projecting therefrom between the arms of the yoke 21 and through an opening 26 in the upper outer side portion of the member 16, as shown, the handle being in clamping position when lowered and in released position when raised to the 30 dotted line position shown in Fig. 3.

20 In the use of this stop means, it is preferable to first position the casket in the hearse in abutment with suitably positioned bier pins 4 at the sides and one end thereof and then to place a stop block 15 and its assembly in engagement with the guide bar 10 through the outer open end thereof and move it into holding or stop engagement with the free end of the casket. The eccentric 25 handle 25 is then thrown down to effect a clamping 35 of the yoke stem and its nut to the guide bar 10.

25 It is apparent that the adjustable stop means embodying the invention provides a simple and 40 easily operable means for holding a casket in carrying position with the hearse, and that it is 45 of a nature to be used in connection with caskets of any size.

30 I wish it understood that my invention is not 50 limited to any specific construction, arrangement or form of the parts, as it is capable of numerous 55 modifications and changes without departing from the spirit of the claim.

Having thus described my invention, what I 55

claim as new, and desire to secure by United States Letters Patent, is:

An adjustable casket stop for hearses, including a guide bar formed to be secured to the upper 5 face of a hearse floor and having a longitudinal slot of inverted substantially T-shape in cross section, a stop block having spaced sides, a bottom, and a vertical front wall, said sides of the block projecting below the bottom, a rubber pad 10 engaged with the under face of the bottom and with the sides of the block and projecting below the sides and seated on the upper side of the bar, an eccentric having ends journaled in the sides

of the block and having a handle, a U-shaped yoke mounted on the eccentric and disposed between the sides of the block, a stem carried by the yoke and extending through the rubber pad, and through the bottom of the block and guided thereby and also extending through the top of the bar, and a member carried by the stem and disposed within the slot and operable to clamp the rubber pad and thereby the block to the bar when the eccentric is in one position and to release the block when the eccentric is in a second position. 5 10

PETER O. KROGH.
